APPARATUS FOR THE PRODUCTION OF
ETCHED COPPER PRINTING CYLINDERSHermann Kindermann, Konighof,
CzechoslovakiaOriginal application January 26, 1934, Serial No.
708,496. Divided and this application July 6,
1935, Serial No. 30,176. In Germany February
4, 1933

1 Claim. (Cl. 101—33)

This is a division of application of Hermann Kindermann, Serial No. 708,496, filed January 26, 1934 and the invention relates to an apparatus for producing etching grounds on copper rollers for textile printing by direct reprint without reversing. There are various methods which render it possible to produce upon copper rollers an etching ground, by the aid of which the rollers can be deeply etched to a pattern. The oldest known process for textile printing consists in scratching the pattern right onto the copper by hand in a roller that has been coated with an etch-proof varnish. Modern processes make use in addition of the help of a pantograph or of electrically actuated scratching devices.

According to other processes, the etching ground is made by copying by means of films, either directly upon a layer which gives the etching ground after exposure and development, or else upon layers which are only converted into the actual etching ground by further treatment.

Other processes are based upon impressing those parts of a design which are subsequently to be deepened by etching, upon the copper roller by offset printing. For this, of course, a reversal of the printing image upon the roller is necessary, quite apart from the fact that in this process the cutting of the pattern has to be effected not in the most advantageous line given by the guide marks, but as nearly as possible along a generating line of the copper roller, or that in the case of the cutting according to the guide marks a portion of the grease ink is transferred back from the copper roller to the offset roller, so that at these positions there is less grease ink upon the copper roller. This phenomenon frequently makes itself perceptible in the ensuing reversal, in the form of faults.

In the case of the hand engraving processes and the mechanical and electrical pantographs hereinbefore mentioned, the employment of autotype and similar lenticular screens is precluded, since these processes can only work with stroke elements and not with point elements. The remaining processes mentioned involve, for the arranging of the individual elements in series, the use of expensive adding machines.

Rouleaux printing rollers need in comparison very deep engraving, and consequently the processes for the production of such rollers hitherto taken over from the technique of re-production exhibit various defects, particularly with respect to the etching ground.

It has now been found that the very powerful etching grounds needed for Rouleaux printing rollers can be obtained by proceeding in such a way that the etching ground is only reprinted in the form of broad margins, and the remaining surfaces are afterwards covered by hand.

An important novel feature of this process consists in the fact that it can be carried out by suitably constructed apparatus, which is described below, with the retouching process known in lithography. It must therefore be regarded as a special advantage that the production of the necessary grease prints on the reprinting paper can be effected by any desired process, such as lithography, letterpress printing, zincography or the like.

The invention herein described and claimed consists in suitably constructed apparatus for carrying out the improved process just described and is illustrated by way of example in the accompanying drawing, in which:

Figure 1 shows in front elevation the means for actuating the lower cylinder of the apparatus with the track shown in section;

Fig. 2 is a diagrammatic view showing the relation of the various parts; and

Fig. 3 shows the apparatus in front elevation.

The machine that has been devised for the carrying out of this process consists essentially of an underframe D, upon which are located three bent standards or plummer blocks L, and L₁, L₂. The plummer blocks L₁ and L₂ support a copper roller or cylinder K, mounted upon a shaft or spindle S_p. A roller G, covered with india-rubber, serves as a counter-pressure roll. The pressing of the india-rubber cylinder G against the copper cylinder K is effected by means of toothed racks Z₁ and Z₂, which are combined with weighted levers H₁ and H₂, and which can be actuated either jointly or individually, according to whether a clutch E is engaged or disengaged. The rubber cylinder G can be moved into and out of its working position, in order that it may not be a hindrance during the further treatment of the copper cylinder, and when it is removed there can be put in its place troughs having various contents, for instance, water, powdered asphalt and so forth. This result is obtained by supporting the india-rubber cylinder G in bobbin-shaped slewing ball bearings KL, which roll upon rails S_{ch}. Each of these rails S_{ch} is formed with a slot SL near the working position of the cylinder G, so that the forked ends G_a of the racks Z₁ and Z₂ can raise the bearings KL and thus press the cylinder G against

the copper cylinder K. The forks Ga are made so wide that the above-mentioned troughs placed upon them can be raised and lowered. The tympan sheet rests upon the top O of a table, which is preferably so adjusted that the upper surface of the top O always lies approximately in the upper tangential plane of the indiarubber cylinder G. This result is best attained if the table can be raised and lowered simultaneously with the roller G by actuating the racks Z₁ and Z₂. The table top O is readily removable, in order to render the copper roller freely accessible for machining. The machine is reversibly driven by an electric motor, through the medium of stepped pulleys or speed cones A.

The transferring to the copper roller preferably proceeds in such a way that the work of retouching is already effected upon the table top O. The indiarubber cylinder G is moved into its operative position underneath the copper roller K, and is located from 2 to 3 centimetres below the latter. Through this gap 2 or 3 centimetres wide the tympan sheet is introduced; and it is to be noted that when this sheet is pressed against the copper roller by the cylinder G, which now takes place, normally no etching ground elements are to come into contact with the copper roller.

When the rollers K and G are under pressure the tympan sheet is now rotated so far between the two cylinders K and G, by pulling with the hand on the counter-shaft belt, that all the

transfer papers are lifted off the sheet and adhere to the copper roller K. After the pressure between the cylinders K and G has been discontinued, the tympan sheet and the table top O are removed, and steps are taken for pulling the transfer papers off the copper cylinder. This is done by renewed pressing of the indiarubber cylinder G according to the nature of the transfer paper, with simultaneous or alternate moistening of the transfer papers, or by letting the copper roller rotate into a trough filled with water placed underneath.

The etching ground transferred in this way to the copper cylinder is reinforced by dusting with asphalt, resin or the like and melting this applied substance, for the purpose of obtaining greater power to resist the etching liquids.

Having now particularly described and ascertained the nature of my said invention and in what manner the same is to be performed, I declare that what I claim is:—

Apparatus for carrying out the process of the character described by the aid of reprinting papers by the tympan or retouching process, including a copper roller, a reprinting roller arranged underneath the copper roller, forks for raising and lowering the reprinting roller, rails on which the said reprinting roller is capable of being moved out thereon, and the rails being formed with apertures for the forks serving for raising and lowering of the reprinting roller.

HERMANN KINDERMANN.
